UNITED STATES PATENT OFFICE.

GEORGE ASSHETON MORGAN, OF NEW YORK, N. Y.

DESIGN FOR RIBBON.

No. 38,507.

Specification for Design.

Patented April 2, 1907.

Application filed January 25, 1907. Serial No. 354,147. Term of patent 3½ years.

To all whom it may concern:

Be it known that I, GEORGE ASSHETON MORGAN, a citizen of the United States, residing at No. 17 Berger avenue, in the city of New York, West Brighton, borough of Richmond, in the county of Richmond and State of New York, have invented a new, original, and ornamental Design for Ribbon, reference being had to the accompanying drawing, in which

the figure is a plan view of a piece of ribbon, showing my new design.

I claim—

The ornamental design for ribbon as shown.

GEORGE ASSHETON MORGAN.
